UNITED STATES PATENT OFFICE.

SAMUEL B. JONES, OF BUTLER, INDIANA.

COMBINED CLOD-CRUSHER, LEVELER, AND HARROW.

SPECIFICATION forming part of Letters Patent No. 576,852, dated February 9, 1897.

Application filed April 24, 1896. Serial No. 588,944. (No model.)

To all whom it may concern:

Be it known that I, SAMUEL B. JONES, a citizen of the United States, residing at Butler, in the county of De Kalb and State of Indiana, 5 have invented a new and useful Combined Clod-Crusher, Leveler, and Harrow, of which the following is a specification.

This invention relates to new and useful improvements in farming implements; and it 10 has for its object to provide a clod-crusher, leveler, and harrow all combined in a single construction and so formed as to permit of its being easily and quickly changed, so as to adapt the same to the character of the work 15 to be performed, and, further, to provide improved means for holding the crusher-bars spaced at a uniform distance from each other.

To this end the invention consists, substantially, in the construction, combination, and 20 arrangement of parts, as will be hereinafter fully illustrated, described, and claimed.

In the accompanying drawings, Figure 1 is a perspective view of a combined clod-crusher, leveler, and harrow constructed in accordance 25 with the present invention. Fig. 2 is a longitudinal sectional view thereof. Fig. 3 is a bottom plan view of the same. Fig. 4 is a detail perspective view illustrating a modification of one of the space-blocks.

Similar numerals of reference indicate corresponding parts throughout the figures.

Referring to the drawings, 1 designates a series of crusher-bars square in cross-section and preferably formed of wood and arranged 35 so as to present one of their corners for action upon the ground. Passing through the crusher-bars 1 and at each end thereof are tie-rods 2, which tie-rods are provided with heads 3 and have the ends opposite thereto 40 threaded to accommodate securing-nuts 4.

For holding the crusher-bars at a uniform distance from each other space-blocks 5 are employed. These space-blocks are each formed of a single piece of wood and have their 45 ends provided with substantially V-shaped notches 6, which notches are adapted to receive the adjacent corners of the crusher-bars 1 when said space-blocks are placed therebetween, and for retaining such space-blocks 50 between the crusher-bars the same are provided with openings 7, through which pass the tie-rods 2. It will therefore be seen that when

the securing-nuts 4 are screwed upon the ends of said tie-rods the blocks 5 are securely held and the crusher-bars 1 will remain at a 55 uniform distance from each other.

In Fig. 4 I have illustrated a modification of one of the space-blocks, which space-block is essentially of the same construction as shown in Figs. 1, 2, and 3, and in this case 60 the same is formed of a single piece of metal and has a V-shaped notch 8 in each of its ends, but the body portion is contracted in order to dispense with superfluous weight.

The crusher-bars 1 are provided throughout 65 their length at suitable intervals with teeth-apertures 9, which apertures are adapted to receive any suitable form of harrow-teeth when it is desired to employ the implement as a harrow. The crusher-bars at the extreme ends of the series also have openings 10, the purpose of which is to receive any 70 suitable form of attaching means whereby draft-animals may be hitched to the same. From the fact that these openings 10 are 75 formed at each end of the series of crusher-bars it will be obvious that the draft may be from either end, thereby permitting the implement to be drawn in a forward or rearward direction. 80

Mounted upon the crusher-bars at each end of the series thereof are also rest-blocks 11, one end of the same being notched to receive the upper corners of the said bars, and disposed above the rest-blocks 11 and held by 85 the latter above the crusher-bars is a longitudinal seat-support 12, which seat-support is secured to the rest-blocks 11 by means of screws or bolts 13, the latter passing through said rest-blocks and into the crusher-bars, 90 thereby securing the rest-blocks thereon. Secured to the support 12 is a seat 14, which may be of any approved construction and upon which the operator of the implement may sit while using the same. 95

From the foregoing it will be seen that I have provided a simple and cheap implement, and the operation and advantages of the same will be readily understood by those skilled in the art. When it is desired to employ the same simply as a crusher, the harrow-teeth are omitted, when the lower corners of the crusher-bars 1 will bear directly upon the ground being worked, and by drawing said 100

crusher-bars over such ground any clods therein will be effectually broken and the same leveled. When required for use as a combined crusher and harrow, the harrow-teeth are inserted in the apertures 9, and it will be apparent that it may be used for such purposes.

While I have illustrated the harrow-teeth as disposed in straight rows, it will be obvious that I may arrange them diagonally or the series of crusher-bars, or in any other preferred manner.

Having thus described the invention, what is claimed as new, and desired to be secured by Letters Patent, is—

In an agricultural implement of the character set forth, a series of square bars arranged in parallel relation with a corner in position to engage with the ground, tie-rods for con-

necting the bars, space-blocks mounted upon the tie-rods between the bars and having V-shaped notches in their ends to receive the corners of adjacent bars, rest-blocks mounted upon the bars and having V-shaped notches in their lower ends to receive the upper corners thereof, a longitudinal seat-support placed upon the rest-blocks, means for securing the seat-support, rest-blocks and bars together, and a seat mounted upon the said support, substantially as set forth.

In testimony that I claim the foregoing as my own I have hereto affixed my signature in the presence of two witnesses.

SAMUEL B. JONES.
